MOWER SHROUD

Robert A. Skyer, Palatine, and George E. Bowman,
Country Club Hills, Ill., assignors to International
Harvester Company, Chicago, Ill.

Filed Jan. 31, 1972, Ser. No. 222,443

Term of patent 14 years

Int. Cl. D15—99

U.S. Cl. D40—1 A

Fig.4.

Fig.5.

Fig.6.

FIG. 1 is a perspective view as seen from the left front of a mower embodying our new mower shroud design; FIG. 2 is a front view as seen front right thereof; FIG. 3 is a front elevational view thereof; FIG. 4 is a top plan view thereof; FIG. 5 is a side elevational view thereof; and FIG. 6 is a back view thereof.

The broken lines being shown for illustrative purposes only.

We claim:

The ornamental design for a mower shroud, substantially as shown and described.
